UNITED STATES PATENT OFFICE.

WILLIAM P. CRARY, OF NEW YORK, N. Y.

DESIGN FOR A LAMP-BRACKET.

SPECIFICATION forming part of Design No. 32,436, dated April 3, 1900.

Application filed March 7, 1900. Serial No. 7,735. Term of patent 3½ years.

To all whom it may concern:

Be it known that I, WILLIAM P. CRARY, a citizen of the United States, residing in the city of New York, borough of Manhattan, in the county and State of New York, have invented and produced a certain new and original Design for a Lamp-Bracket, of which the following is a full, clear, and exact specification, reference being had to the accompanying drawing, forming part thereof and showing a perspective view of the bracket.

The leading feature of my design is the flattened tubular body having a thin arm extending from one plane face and provided with a deep notch and radial depressions at its rounded end.

Referring to the drawing, A is the body or flattened tubular portion having two plane

faces joined by the curved ends A' A'. The arm B projects outwardly at a right angle from the central line of one plane face of the body. It is of less height than the body and has its outer end B' rounded and provided with the deep angular notch b and radial depressions b', as shown.

I claim—

The design for a lamp-bracket herein shown and described.

In testimony that I claim the invention above set forth I affix my signature in the presence of two witnesses.

WILLIAM P. CRARY.

Witnesses:

CHARLES R. SEARLE,
FRANK G. STARK.
